Justin G. Sanders; Dean G. Stathakis**CLAIM**

The ornamental design for an eyeliner application device, as shown and described.

DESCRIPTION

FIG. 1 is a perspective view showing my new design for an eyeliner application device;

FIG. 2 is a front view thereof;

FIG. 3 is a rear view thereof;

FIG. 4 is a side view thereof;

FIG. 5 is a top view thereof;

FIG. 6 is a bottom view thereof; and,

FIG. 7 is another perspective view showing the eyeliner application device in use.

The broken lines are for illustrative purposes only and form no part of the claimed design.

1 Claim, 2 Drawing Sheets---
